CARL KUPFER, OF NUEREMBERG, GERMANY, ASSIGNOR TO THE FIRM TRIUMPH-WERKE
NUERMBERG A.-G., OF NUEREMBERG, BAVARIA, GERMANY.

FREE WHEEL FOR THE PLATEN OF TYPEWRITING MACHINES.

Application filed August 1, 1921. Serial No. 489,127.

To all whom it may concern:

Be it known that I, CARL KUPFER, a citizen of the German Republic, residing at Nuremberg, Germany, have invented certain new and useful Improvements in Free Wheels for the Platens of Typewriting Machines, of which the following is a specification.

It is known to insert a coupling device or free wheel between the platen and line spacing wheel of a typewriting machine so as to enable the platen to be rotated independently of the line spacing wheel. This invention has for its object to improve the construction of such coupling device to render the platen readily detachable. According to the invention the platen spindle is made in two parts which fit into a tubular connecting member, one of such parts being movable longitudinally and connected with the line spacing wheel coupling.

In order that the invention may be clearly understood, I shall proceed to describe the same with reference to the two forms of construction shown by way of example in the accompanying drawings, wherein

Figs. 1 to 7 relate to the first form of construction and Figs. 8 to 11 to the second form of construction.

Figures 1^a and 1^b show the platen and associated parts in axial section,

Fig. 2 is a part axial section taken at right angles of the plan of section of Figures 1^a and 1^b.

Figures 3 and 4 are end views of the coupling members,

Figures 5 and 6 are detail views of the locking device for the movable part of the platen spindle,

Figure 7 is an elevation of the platen spindle,

Figure 8 is an axial section through the platen,

Figure 9 is a view of the platen spindle,

Figure 10 is an axial section of the platen and ratchet wheel on a plane at right angles to the plane of section of Figure 6.

Figure 11 is a section taken through the coupling arms showing the platen with the coupling in un-coupled position, the hand wheel, the un-coupling button and the locking device being shown in elevation.

The first form of construction is as follows:

The platen spindle comprises two parts

1^a and 1^b, connected to one another by means of a tubular connecting piece 2 fixed in the platen 3. The part 1^a of the spindle is rigidly fixed to the platen by means of the screw 4 and is mounted in a bearing 5. The hand wheel 6 is fixed on the outer end of the part 1^a as shown in Figure 1^b. A collar 8 fixed upon a tubular connecting piece 2 by means of a screw 7 serves as an abutment for one end of a spiral spring 9 which is pushed over the tubular connecting piece 2, the other end of this spring 9 bearing against a sleeve 10 which is slidably mounted upon the tubular connecting piece 2.

The cross pin 11 passing through the sleeve 10 slides in a longitudinal slot 2^a in the tubular connecting piece 2 and engages in an axial slot 1^c cut in the end of the part 1^b of the platen spindle. The sleeve 10 can thus be shifted longitudinally upon the tubular connecting piece 2, rotation of the part 1^b of the platen spindle in the connecting piece 2 being prevented, so that there is a rotary driving connection between the part 1^b and the platen.

An axially directed fork 12 fixed upon a sleeve 10 has two diverging slots 13 and 14 which engage studs 15 and 16 respectively, fixed to axles 17 and 18 respectively mounted longitudinally in the platen. Each of the axles 17 and 18 projects through the end of the platen and carries an eccentric 19, 20, which form a frictional driving clutch between the platen and the rotatable ratchet wheel 21.

The part 1^b of the platen spindle projects through a bearing 22 which has a cavity 23 within which projects a spring actuated locking lever 24, adapted to engage a conical abutment 1^a on the member 1^b. The cavity 23 has an internal screw mounted at its outer end, into which is screwed a cap 25 having an opening through which the part 1^b of the spindle projects. The conical abutment 1^a is designed to limit the outward movement of the part 1^b of the spindle under the action of the spring 9. The usual hand wheel 26 is fixed to the outer end of the part 1^b of the spindle and a hand lever 27 is provided as a counter bearing for use when the hand wheel 26 is pressed inwardly to release the platen from the line spacing wheel.

The operation of the device is as follows: When part 1^b of the spindle is pushed in

the direction of the arrow *a* by pressing upon the hand wheel 26 the cross pin 11 and the sleeve 10 are caused to slide axially against the action of the spring 9 carrying with them the fork 12. The oblique slots 13 and 14 in the fork 12 cause the axles 17 and 18 and their eccentrics 19 and 20 to be rotated in opposite directions, thereby causing the eccentrics to come out of contact with the inner wall of the ratchet wheel 21, so that the platen is disconnected from the ratchet wheel and can be rotated independently of the latter.

At the end of this movement the conical stud 1^a passes under the spring actuated locking lever 24 which snaps past the stud 1^a and locks the part 1^b of the platen spindle against return movement under the action of the spring 9. The platen therefore remains disconnected from the line spacing wheel.

When it is desired to couple the platen with the line spacing wheel again, the locking lever 24 is rocked by hand so that the part 1^b of the spindle is released and is brought back to its initial position by the action of the spring 9, the studs 15 and 16 and the eccentrics 19 and 20 being also returned to their initial positions, so that the driving connection between the ratchet wheel and the fork is re-established.

To remove the platen from the typewriter machine, it is merely necessary to unscrew the cap 25 and release the screw 4, whereupon parts 1^a and 1^b of the platen spindle can be withdrawn and the platen removed. The platen can be mounted in position again in an equally simple manner, by reversing the process.

40 The second form of construction which is illustrated in Figures 8 to 11, differs from the first merely in the elements which control the coupling between the platen and the line spacing wheel.

45 Whilst according to the first form of construction the part 1^b of the platen spindle is used for releasing the coupling as well as for rotating the platen by hand, according to the second form of construction a separate element is provided for each of these operations.

50 A tube 2^a corresponding in diameter to the tubular sleeve 2 encloses the part 1^b of the platen spindle and carries a hand wheel 26^a. The tube 2^a has at its outer end an angular slot forming part of the bayonet joint for axially moving the part 1^b of the platen spindle. The tube 2^a is coupled to the tubular sleeve 2 by means of a claw like engagement between the two tubes, and the tubes are secured in the coupled position by means of a locking screw 28^a engaging with a boring 28. In this manner any play on the part of the platen during rotation of 65 the hand wheel is prevented.

The part 1^b of the platen spindle is axially movable in the tube 2^a and is rotatable therein so far as the bayonet joint permits. The amplitude of the axial movement depends on the distance through which the sleeve 10 is to be shifted to release the coupling. The bayonet joint comprises a stud 29 fixed in the part 1^b of the platen spindle and engaging in the angular slot 30 of the tube 2^a said stud 29 entering into a notch 30^a in the slot 70 when the part 1^b of the spindle is rotated relatively to the tube 2^a whilst the latter is at the extreme inner end of its movement.

A nob 31 fixed on the outer end of the part 1^b of the platen spindle facilitates manipulation, the inner end of the said part 1^b being cut square and bearing against the cross pin 11 during the operation of releasing the coupling.

This form of construction operates as follows: Upon movement of the part 1^b of the platen spindle in the direction of the arrow *a* (Figure 8) the cross pin 11 and the coupling sleeve 10 are shifted against the action of the spring 9, thereby releasing the 85 coupling in the manner described with reference to the first form of construction of the invention. When it is required to lock the coupling in an uncoupled position the part 1^b of the spindle is held against return 90 movement under action of the spring 9 by bringing the stud 29 into engagement with the notch 30^a by a slight rotation. The coupling between the platen and line spacing wheel is thus maintained in disconnected 100 position and the platen can be adjusted by rotating the hand wheel 26^a. Conversely the line spacing wheel can be coupled to the platen 3 again by releasing the bayonet joint 29, 30.

105 The platen 3 can easily be removed as upon loosening of the locking screws 4 and 28^a the parts 1^a and 1^b of the platen spindle together with the tube 2^a can be withdrawn, whereupon the platen can be removed.

I claim:—

1. Free wheel for the platen of typewriting machines comprising in combination with the platen and with the ratchet wheel, 115 a platen spindle composed of two parts of which one is fixed to the platen the other being mounted in the same so that it can be moved in longitudinal direction, a tubular sleeve in the platen for connecting the said two parts of the spindle, and an eccentric inserted between the said ratchet wheel and said platen and connected with said movable part of said spindle so that it can be turned with regard to the platen 120 when said movable part of the spindle is being moved.

2. Free wheel for the platen of typewriting machines comprising in combination with the platen and with the ratchet 130

- wheel, a platen spindle composed of two parts of which one is fixed to the platen the other being mounted in the same so that it can be moved in longitudinal direction, 5 a tubular sleeve in the platen for connecting the said two parts of the spindle, and two eccentrics inserted between the said ratchet wheel and said platen and connected with said movable part of said spindle so 10 that they can be turned with regard to the platen when said movable part of the spindle is being moved.
3. Free wheel for the platen of typewriting machines comprising in combination with the platen and with the ratchet wheel, a platen spindle composed of two parts of which one is fixed to the platen the other being mounted in the same so that it can be moved in longitudinal direction, 15 a tubular sleeve in the platen for connecting the said two parts of the spindle, two eccentrics inserted between the said ratchet wheel and said platen, axial pivot bolts of said eccentrics, radial studs of said pivot 20 bolts, and an axial fork connected with said movable part of the spindle and having oblique slots with which said radial studs engage so that said eccentrics are turned when said movable part of the spindle is 25 moved in longitudinal direction.
4. Free wheel for the platen of typewriting machines comprising in combination with the platen and with the ratchet wheel, a platen spindle composed of two 30 parts, one of which is fixed to the platen the other one being mounted in the platen so that it can be moved in longitudinal direction and having a cross boring, a tubular sleeve in the platen for connecting said two 35 parts of the spindle having a longitudinal slot, a coupling sleeve upon said tubular sleeve, a cross pin of said coupling sleeve traversing said slot of the tubular sleeve and said boring of the movable part of the 40 spindle, an axially directed fork fixed to 45 said coupling sleeve having two oblique guide slots, two eccentrics engaging with said ratchet wheel, axially directed axles of said eccentrics, radial studs of said axles 50 engaging with said oblique slots of said fork so that when said movable part of the spindle is moved in longitudinal direction said eccentrics are brought out of en-
- gagement with said ratchet wheel, and a spring acting upon said coupling sleeve 55 for maintaining the same in the coupling position.
5. Free wheel for the platen of typewriting machines comprising in combination with the platen and with the ratchet wheel, a platen spindle composed of two parts of which one is fixed to the platen the other being mounted in the same so that it can be moved in longitudinal direction, 60 a tubular sleeve in the platen for connecting the said two parts of the spindle, the coupling members of the free wheel connected with said movable part of the spindle, a conical collar upon the outer part of said movable part of the spindle, a bearing for said movable part having a cavity corresponding with said conical collar and a slot, a locking lever projecting through said slot of the bearing and engaging with said conical collar so that said conical collar can be brought in engagement with said cavity of the bearing in order to lock said movable part of the spindle in the free 65 wheel position of the platen.
6. Free wheel for the platen of typewriting machines comprising in combination with the platen and with the ratchet wheel, a platen spindle composed of two 70 parts of which one is fixed to the platen the other being mounted in the same so that it can be moved in longitudinal direction, 75 a tubular sleeve in the platen for connecting the said two parts of the spindle, and the coupling members of the free wheel connected with said movable part of the 80 spindle, a hand wheel upon the outer end of said movable part of the spindle, a tube enclosing said movable part of the spindle having an angular slot with a notch and a bolt of said movable part of the spindle engaging with said angular slot of the tube for locking the said movable part of the 85 spindle in the free wheel position of the 90 platen.
- In testimony whereof I affix my signature 95 in presence of two witnesses.
